CLAIM

The ornamental design for a sea scooter as shown and described.

DESCRIPTION

1. Sea scooter

1.1: Front

1.2: Rear

1.3: Left

1.4: Right

1.5: Top

1.6: Bottom

1.7: Front, Left Perspective

1.8: Bottom, Rear Perspective

The broken lines depicting a boundary around the de-emphasized elements, and the de-emphasized elements within, illustrate portions of the diving scooter which form no part of the claimed design.
